(57) **CLAIM**

I claim the ornamental design for a frame, as shown and described.

DESCRIPTION

FIG. 1 is a front view of a frame showing my new design;

FIG. 2 is a rear view thereof;

FIG. 3 is a top view thereof;

FIG. 4 is a bottom view thereof;

FIG. 5 is a left side view thereof;

FIG. 6 is a right side view thereof; and,

FIG. 7 is a perspective view thereof.

The dash-dash broken lines depict portions of the frame that form no part of the claimed design. The dash-dot-dash broken lines illustrate a boundary of the design that form no part of the claimed design.
